UNITED STATES PATENT OFFICE

THOMAS F. LEAHY, OF CHICAGO, ILLINOIS, ASSIGNOR TO AMERICAN HOTEL REGISTER CO., OF CHICAGO, ILLINOIS, A CORPORATION OF ILLINOIS

INKWELL

Application filed February 10, 1927. Serial No. 167,080.

This invention relates to pen holder and ink well constructions of the type wherein the pen holder when not in use is adapted to be mounted in a handy position on the ink well forming a stopper for the ink well, and with the pen in the ink ready for instant use.

One of the principal difficulties obtaining in constructions of the above type, such as used in the past, has been the smearing of the ink over the lower portion of the holder and the soiling of the hand when the pen was being used. In some of the constructions of the above mentioned type, particularly where the lower portion of the pen holder was adapted to act as a stopper, the latter usually became incrusted with ink to such an extent, that it would stick in the well and not infrequently result in the splashing of ink upon the sudden loosening and withdrawing of the holder.

It is accordingly an object of this invention to provide a construction of the above type in which the pen holder is mounted in a handy position on the ink well with the pen in the ink when not in use, the lower portion of the holder acting to seal the entrance of the pen to the well in a manner which will, to a considerable extent, prevent evaporation of the ink.

It is also an object of this invention to provide a construction of the above type in which the lower portion of the pen holder acts as a stopper of the entrance for the pen to the well, the said holder and entrance being so constructed that the holder is not likely to stick from an accumulation of ink thereon or in the entrance.

It is further an object of this invention to provide a construction of the above type in which the entrance for the pen to the ink well is so constructed that a minimum of the ink which may be splashed on the side of the entrance will come in contact with the holder.

Another object of my invention is to provide a construction of the above type in which the pen is provided with a stopper adapted to support the pen in the well with the point of the pen in the ink and a flared guard above the stopper to prevent the ink from soiling the hand of a person using the pen.

Other and further objects are accomplished by providing a construction and arrangement of the various parts in the manner herein-after described, and particularly pointed out in the appending claims.

Referring to the drawings:

Fig. 1 is a plan view of an ink well embodying this invention and with the pen removed,

Fig. 2 is a vertical section taken at the line 2—2 of Fig. 1, and showing the pen in elevation,

Fig. 3 is an enlarged vertical section of the supporting block for the pen removed from the ink well, and

Fig. 4 is an enlarged detail view taken from the end of the ferrule for the pen holder.

Referring to the drawings more particularly, numeral 5 refers generally to the ink well, which in this instance is in the form of a prismatic block of glass, having a well 6 therein adapted to contain ink, and a supplemental well 7 adjacent to and joining said well 6. The main well 6 is normally closed by a cover 8 having a depending flange 9 around its edges adapted to surround a raised shoulder 11 at the upper edge of said well. The block 5 is provided with a recess 12 above the supplemental well 7 to receive a separable block 13 in the entrance thereto.

The block 13 is preferably made of a suitable composition, such as bakelite, and is apertured as at 10 to provide the entrance to the supplemental well 7 for the pen 14 and is adapted to support said pen in a handy position with the point thereof in the ink.

The pen 14 is provided with a flared guard 15 near its lower end and a ferrule 16 preferably of bakelite below said guard, said ferrule acting as a stopper to seal the entrance to the well 7, in order that the ink therein will not evaporate when the pen is not in use. A circular shoulder 17 of a diameter less than that of the guard 15 and formed at the upper end of the ferrule 16 abuts the lower face of said guard and its lower face in turn rests upon a circular shoulder 18 formed in the block 13 at the upper end of the aperture 10. The guard 15 being separated from the shoulder 18 by the shoulder 17 of a diameter less

than that of the guard ink is less likely to reach the pen holder above the guard than if the latter contacted said shoulder 18 directly or the shoulder 17 were of as large a 5 diameter as said guard. For the same reasons the fingers are less apt to come in contact with ink. The shoulder 18 is formed at the bottom of a circular recess 19 in the upper end of the block 13 for receiving the shoulder 17 and the 10 guard 15. A cylindrical serrated portion 21 of very slightly reduced diameter is formed on the ferrule 16 directly below the shoulder 17, its axis being preferably normal to the plane of the shoulder and in coincidence with 15 the axis of the pen. The portion 21, together with said shoulder 17 cooperates with the shoulder 18 of the block 13 to form a seal therewith for reducing the evaporation in the well. The shoulder 17 and portion 21 thus 20 have very little area actually in contact with the shoulder 18.

As a further precaution, in order that as little area of the ferrule may come in contact with the block 13 as possible, so as to reduce 25 any tendency of the ferrule to accumulate ink, the said block is provided with an outwardly flared and bulged portion 22 beneath the shoulder 18, the lower end of the aperture 10 being considerably larger than the 30 upper end thereof and the ferrule 16 is provided with an inwardly tapered or reduced portion 23 directly below the portion 21 thereof and normally adjacent the bulge or flare 22. The reduced portion 23 extends between 35 the portion 21 and a circular rim 20 at the lower end of the ferrule and said rim is adapted to contact the inner wall of the entrance to maintain the pen in predetermined sloping position where it may be conveniently 40 grasped by the hand of the user. Thus the pen may be maintained in the desired sloping position at a predetermined depth in the entrance with the pen in the ink in such a manner that the pen does not touch the entrance 45 of the well and therefore cannot smear the entrance. The shoulder 18, it is to be noted, is at the outer end of the entrance to the well and forms except for the very reduced area of contact afforded between the rim 20 and 50 the inner walls of the entrance, the principal contact between the entrance and the pen. By this construction not only is the pen point kept from smearing the entrance as much as possible but any ink that may possibly become 55 lodged within the entrance is kept from smearing the ferrule and from reaching the hands of the user above the flared guard 15.

The ferrule 16 and the block 13 as above stated are preferably of bakelite as this substance 60 does not retain ink as does hard rubber for instance, and at the same time is flexible enough to be capable of withstanding rough usage as when the pen is roughly inserted in the well.

65 From the foregoing description, it will be

apparent that the construction provides an efficient combination of an ink well and pen in which the pen, when mounted in the well is always ready for use, and at the same time forms a stopper for the well, which stopper is not likely to stick in the well, but cooperates with the block 13 to form an efficient mounting for the pen.

While in the above construction I have described one embodiment which my invention may assume in practice, it will of course be understood that the same is capable of modification and that modification may be employed without departing from the spirit and scope of my invention.

I claim:

1. In combination, an ink well having an opening in its upper portion and a closure member therefor, a cylindrically walled passage through said member the upper end of which is surrounded by an annular seat whose axis is inclined, a penholder having an annular shoulder and surface thereon normal to the penholder axis adapted to fit snugly without wedging on said seat and having below the shoulder a short serrated cylindrical surface adapted to fit snugly without wedging within said cylindrical walled surface when the penholder is squarely seated in a predetermined inclined position for preventing movement of the penholder laterally of its axis and longitudinally downwardly, a downward extension on said closure member, a reduced portion of the penholder below said serrated surface having contact, when the penholder is squarely seated, with a surface on said extension at any of a plurality of points about the circumferential surface of said reduced portion equi-distant from its axis.

2. In combination, an ink well having an opening in its upper portion and a cover therefor, the cover having a recess in its top surface, an inwardly extending annular shoulder at the bottom of the recess, a cylindrically walled passage through said recess within said shoulder, the top face of said shoulder being a plane surface inclined at an angle to the horizontal, a penholder having an annular shoulder the bottom face of which is adapted to seat flatly on said top face forming therewith and with the penholder ferrule a seal for said passage, the penholder above its said shoulder being flared outwardly therebeyond forming a finger guard, a ferrule just below the penholder shoulder having serrations whose outer surfaces coincide with a common cylindrical surface coaxial with the penholder and of a diameter causing the serrations to fit snugly without wedging within the walls of said passage, the lower portion of the ferrule being reduced and having an annular contact surface coaxial with the penholder and parallel to the shoulder faces for contacting with a cooperating

contact surface on said cover below said shoulders to balance the penholder in a passage sealing position at the same inclination in any position of the penholder in angular rotation about its own axis.

5 In witness of the foregoing I affix my signature.

THOMAS F. LEAHY.
